(57) **CLAIM**

The ornamental design for a handle holder, as shown and described.

DESCRIPTION

FIG. 1 is a perspective view of a handle holder, showing my new design;

FIG. 2 is a top plan view thereof;

FIG. 3 is a bottom plan view thereof;

FIG. 4 is a front elevational view thereof;

FIG. 5 is a rear elevational view thereof; and,

FIG. 6 is a right side elevational view thereof; the left side elevational view being a mirror image thereof.

The broken lines in FIG. 4 depict a portion of the handle holder that form no part of the claimed design.

1 Claim, 6 Drawing Sheets
